CLAIM

The ornamental design for a pocketed panel for attachment to a chair back, as shown and described.

DESCRIPTION

FIG. 1 is a front elevational view of the pocketed panel for attachment to a chair back showing my new design,

FIG. 2 is a front elevational view,

FIG. 3 is a top plan view; and

FIG. 4 is a right side elevational view thereof.

The rear view is plain and conventional in appearance.

FIG.4

FIG.3

FIG.2
